VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-DOOR-OPERATING DEVICE.

1,078,321.

Specification of Letters Patent. Patented Nov. 11, 1913.

Application filed July 3, 1912. Serial No. 707,637.

To all whom it may concern:

Be it known that I, VICTOR M. SUMMA, residing at St. Louis, Missouri, and being a citizen of the United States, have invented 5 certain new and useful Improvements in Car-Door-Operating Devices, (Case A.) of which the following is a full, clear, and exact description, such as will enable others skilled in the art to which it appertains to 10 make and to use the same, reference being had to the accompanying drawings, which illustrate the preferred form of the invention, though it is to be understood that the invention is not limited to the exact details 15 of construction shown and described, as it is obvious that various modifications thereof will occur to persons skilled in the art.

In said drawings: Figure 1 is a transverse sectional view taken on line 1, 1 of Fig. 2; 20 that is, taken transversely through a car equipped with the invention, and Fig. 2 is a longitudinal sectional view of the car, the section being taken on line 2, 2 of Fig. 1.

The object of the invention is to provide 25 a simple door lifting and locking and releasing device, adapted to be applied to the hinged doors of dumping cars, of the class commonly known as general service cars, the principal object being to provide simple, durable and efficient means for operating the 30 doors, which will positively lift and will lock the doors when the same are lifted to their closed position, and which will unlock and positively release the doors when they 35 are in their closed position.

Referring to the parts: F indicates a center sill or central girder, which may be of any approved type of construction.

H represents generally a cross-bearing 40 member commonly incident to car under-frame constructions, which is connected with the center sill by means of rivets G, passing through the flanges of the members H and through the webs of the center sill.

I is a bottom tie plate connected with the 45 diaphragms H and extending below the center sill.

B B indicate angles which are commonly

used as the bottom or tension angles of plate girder side walls, which side walls are not 50 shown, and S indicates the doors of the car.

a, a are cover plates for the cross-bearing members H.

Connected with each of the doors and 55 preferably near each side of each door are brackets 1, which in form resemble channels with outstanding horizontal flanges 2, which brackets 1 are connected by through rivets 3 with the doors S, leaving the open channel 60 or spaces between the doors and the bottoms of the brackets 1, within which are slidably 65 mounted locking bars 4. These locking bars are preferably formed each of a single piece bent back upon itself, as shown in Fig. 1, to form loops 5, and are of sufficient 70 length to project beyond the outer edges of the doors to form locking bolts 6, which locking bolts are adapted to pass through loops in the hangers 7, which hangers are secured in position by being projected 75 through the horizontal flanges of the angles B, before referred to, and held in position by nuts 8 on the upper ends of said loops 7.

Connected with the cross-bearers H, in 75 any preferred manner, are bearings 9, which form seats for the crank arms 10 of shafts 11, which shafts are rockable in the bearings 9 and within the loops 5, before referred to.

Assuming the door S to be open, as shown 80 at the right-hand side of Fig. 1, the shaft 11 is rocked in a clock-wise direction, as indicated by the dotted line and arrow in Fig. 1. This rocking of the shaft 11 will cause 85 retraction of the bolt 6 through engagement of the loop 5 with said shaft until the door reaches a horizontal position, at which time continued rotation of the shaft 11 in the same direction will cause the bolt 6 to be 90 projected beyond the outer edge of the door and into engagement with the loop 7, before referred to, and at the same time the shaft 11 is relieved from the weight of the door 95 and the door is supported by locking bar 6 engaging with the loop 7. When it is desired to open the door, the shaft 11 is rocked

- in an opposite direction, the shaft coöperating with the loop 5 to retract the bolt 6, thereby permitting the door to drop by gravity, but if, for any reason, the door should stick 5 and refuse to drop by gravity, the interengagement of the shaft 11 and loop 5 will cause the door to be pulled downwardly, so as to break any seal (such as an ice seal) which may have been formed.
- 10 It is to be observed that the doors S are not pivoted to the center sill or center girder F, but are supported upon brackets 15, which are riveted directly to the web of the center sill, and are so proportioned with relation to the top flange 16 of the center sill that the inner edges of the doors in closing will be carried some little distance below said top flanges 16, thus dispensing with the usual sill cover plate, which is common in 15 car constructions of this type.
- 15 It is to be observed that the forward extension 5^a of the loop 5 will abut the rear inner edge of the bracket 1 when the bolt 6 is fully projected, thereby preventing rotation of the shaft 11, which rotation, if permitted, would allow the door to drop.
- 20 What I claim is:—
1. In a car, in combination with the frame of a car, a pivoted door, a shaft pivotally mounted adjacent the door bearing against and supporting said door and sliding mechanism carried by said door, whereby said shaft revolving in opposite directions, moves the door in opposite directions.
  2. In a dumping car, the combination of a side tension angle having a door supporting loop secured thereto, a pivoted door, a bracket fastened to the underside of said door, a locking bar slidably mounted in said 40 bracket, and adapted to be projected beyond the adjacent end of the door into said loop, and a rockable shaft in constant engagement with the loop.
  3. In a dumping car, the combination of a side tension angle having a loop secured thereto, a pivoted door, a bracket fastened to said door, a locking bar slidably mounted in said bracket, and adapted to project beyond the adjacent end of the door into 50 said loop and means beneath said door to actuate said locking bar.
  4. In a dumping car, the combination of a side tension angle having a loop secured thereto, a pivoted door, a bracket fastened to said door, a locking bar slidably mounted in said bracket, and adapted to project beyond the adjacent end of the door into said loop and a swinging shaft actuating said locking bar.
  5. In a dumping car, a hinged door, a 60 slidable bolt having an outer edge adapted to project from an edge of said door and having the inner end bent into a loop and

door actuating means engaging said loop thereby to actuate the bolt.

65

6. In a dumping car having a holding loop, a hinged door, a bolt carried by said door, means positively actuating said door in both directions, said means connected to said bolt to project the same into and from 70 said loop.

7. In a dumping car having a holding loop, a hinged door, a bolt carried by said door, means positively actuating said door in both directions, said means connected to 75 said bolt to project the same into and from said loop, and means limiting the outward movement of said bolt.

8. In a dumping car, a door hinged along one edge, a locking means carried by said 80 door adjacent the opposite edge, door actuating means moving in an arc in a plane at right angles to said hinged edge and engaging the underside of the door, said means directly connected to said locking means to 85 actuate the same.

9. In a dumping car, a door, a rocking shaft movable in an upward direction and directly supporting said door and door locking mechanism carried by said door and 90 actuated by the outward movement of said shaft.

10. In a dumping car, a door, a rocking shaft movable in an upward direction and directly supporting said door and door locking mechanism carried by said door, said 95 locking mechanism constituting the means for positively lowering said door.

11. In a dumping car, a hinged door, locking means carried by said door, a rocking shaft movable in an upward direction, 100 to actuate the door and an outward movement of said shaft actuating the locking means.

12. In a dumping car, a hinged door, locking means carried by said door, a rocking shaft movable in an upward direction, the 105 said movement of said shaft actuating the door and an outward movement of said shaft actuating the locking means, and 110 means limiting the rocking of said shaft.

13. In a dumping car, a hinged door, a bolt carried by said door, and a crank shaft directly engaging said bolt to actuate the same.

14. In a car door mechanism comprising a crank shaft adapted positively to actuate the door to open and close the same, and a locking means continuously actuated by the movement of said shaft.

15. In a dumping car, a hinged door, a crank shaft supporting said door and means directly connected to said shaft for locking and unlocking said door.

16. In a dumping car, a hinged door, a 125 crank shaft supporting said door in all of

115

120

125

its positions and longitudinally slidable locking means carried by the door loosely engaged by said shaft to open and close said door.

5 17. In a dumping car, a hinged door, a locking means carried by the door and a crank arm connected to said means and adapted to positively lower the door.

18. In a dumping car, a hinged door and
10 a two-part mechanism constituting pivot-

ally connected means for positively lowering, lifting and locking said door, comprising a rockable shaft and a slidable bolt.

In witness whereof I have hereunto set
my hand in the presence of two witnesses. 15

VICTOR M. SUMMA.
